BIRD FEEDER

Michael S. Gallo, Racine, Wis.

Application May 31, 1955, Serial No. 36,287

Term of patent 14 years

(Cl. D31—2)

Fig. I

Fig. II

Fig. III

Fig. I is a perspective view of a bird feeder embodying my new design:

Fig. II is an elevational end view of the bird feeder:

Fig. III is an elevational side view thereof.

I claim:

The ornamental design for a bird feeder, or analogous article, substantially as shown.
